UNITED STATES PATENT OFFICE:

ABNER DOBLE, OF WALTHAM, MASSACHUSETTS, ASSIGNOR TO GENERAL ENGINEERING COMPANY, OF DETROIT, MICHIGAN, A CORPORATION OF MICHIGAN.

HYDROCARBON-ENGINE.

1,232,777.

Specification of Letters Patent. Patented July 10, 1917.

Application filed October 1, 1912. Serial No. 723,417.

To all whom it may concern:

Be it known that I, ABNER DOBLE, a citizen of the United States, and resident of Waltham, county of Middlesex, State of Massachusetts, have invented certain new and useful Improvements in Hydrocarbon-Engines, of which the following is a specification.

This invention relates to hydrocarbon engines and more particularly to improved mechanism for economically feeding variable quantities and compositions of fuel to the engine.

It has been proposed heretofore to force a large quantity of mixture into the engine cylinder and thereby get great power. The result sought has been attained, but the efficiency of engines utilizing large quantities of fuel is very low because much fuel is wasted by the devices at present used for this purpose.

It is one of the objects of this invention to increase the efficiency of hydrocarbon engines so that an increased power may be economically obtained where desired, as in climbing hills, racing or accelerating quickly.

A further object of the invention is to provide a device in which the proportion and pressure of the mixture may be varied, and one in which a more homogeneous mixture may be obtained than is ordinarily obtained in high power engines.

The above and other objects and the novel features of the invention will be apparent from the following description taken in connection with the drawing in which—

Figure 1 is a side elevation, parts being in section, showing a well known type of engine embodying my improvements;

Fig. 2 is an enlarged sectional view of the vaporizing and mixing tube.

In the drawing the improvement is shown as embodied in the well known Knight engine. However, it is to be understood that the invention is not limited to such an engine, but may be applied to any ordinary internal combustion engine.

The numeral 10 designates the cylinder casing which has a dome shaped head 11 providing a dome shaped ignition chamber 12 on the interior communicating with the piston chamber 13. 14 designates the ordinary spark plug or other igniting arrangement and 15 and 16 are sleeve valves con-

trolling the admission and exhaust of the explosive and exploded mixture. The piston 17 reciprocates within the cylindrical sleeve 16 and is connected to a rod 18 which transmits the power to a crank shaft and driving mechanism not shown. An exhaust pipe 19 is secured to the cylinder and communicates with an exhaust opening 20 which is placed in communication with the chamber 13 when the ports in the cylinder 15 and 16 are in proper relation. An admission opening 21 is likewise placed in communication with the chambers 12 and 13 when the relation of the valves 15 and 16 is such as to place the ports therethrough in alinement.

A mixing chamber is provided on the exterior of the cylinder and comprises a substantially U-shaped tube 22 which is secured to the cylinder wall 10 by means of a flange 23 at one end thereof. As indicated, the tube 22 is formed in one piece with the flange 23 and also is formed integral with a manifold one opening of which is indicated at 22'. It is to be understood, of course, that the mixing tube 22 may be applied to a single cylinder or a plurality of cylinders. The tube 22 flares outwardly at its other end 24 and means may be provided to more rigidly support said end on the cylinder head. The tube or mixing chamber is provided with one or more contracted sections 25 near the flaring end. The shape of the tube near its inlet in longitudinal cross section, therefore, corresponds to the shape of the well known Venturi meter. The contraction of the cross sectional area of the tube changes the velocity of the incoming air and hydrocarbon and has the effect of producing a more homogeneous mixture than is ordinarily obtained.

A conical spider 26 having a plurality of radially arranged air admission inlets 27 is rigidly mounted on the flaring end 24 of the mixing tube 22. A shutter 28, a counterpart of the spider 26, is mounted to slide on the outer surface of the spider and vary the effective area of the air admission openings 27 so as to regulate the amount of air introduced into the mixture. A lever 29 secured to the shutter 28 is connected by a lever 30 to a rod 31 which may be controlled by the steering column 32 and steering wheel 33 usually provided on an ordinary motor vehicle.

A tank 34 is provided which is suitable for containing the fluid hydrocarbon and an air pump 35 operated from the engine shaft or other suitable driving means has 5 its cylinder connected to the tank 34 by means of the pipe 36 and maintains the hydrocarbon in the tank under a certain pressure, preferably about 50 pounds.

To conduct the hydrocarbon to the mixing 10 chamber a pipe 37 is provided which has a nozzle 38 at its end where it discharges into the mixing tube 22. The spider 26 and shutter 28 have central hubs 261 and 281 arranged to receive and support the pipe leading 15 to the nozzle and the nozzle at the center of the flaring inlet 24 so that the stream from the nozzle will spray through the contracted section 25. Between the nozzle 38 and the tank 34 there is a needle valve 39 which serves to regulate the amount of the 20 gasoline or other fuel supplied from the tank 34. The valve 39 is preferably controlled from the steering column by means of the levers 40 and 41 and the rod 42, as 25 in the case of the air admission, but it will be obvious that these valves may be controlled from other positions about the vehicle or engine, if desired.

Between the needle valve and the nozzle 30 the supply pipe 37 is formed in a conical spiral 43 to lie in contact with the dome shaped cylinder head 11. The spiral 43, nozzle 38 and flaring end of the tube 22 are therefore supported from the cylinder head. 35 The spiral is for the purpose of utilizing part of the waste heat of the motor to vaporize the hydrocarbon and thereby obtain a more homogeneous mixture of the air therewith when the vapor issues from 40 the nozzle 38 into the mixing tube 22. The spiral being mounted on a portion of the cylinder which is not water-jacketed receives considerable of the waste heat of the cylinder and due to this heating and vaporizing, 45 the hydrocarbon makes an excellent mixture and greatly increases the pressure in the mixing tube and at the inlet of the motor cylinder. When the inlet valves opening into the cylinder or cylinders are operated, 50 a much greater amount of hydrocarbon mixture is introduced than by atmospheric pressure due to the comparatively feeble suction of the ordinary engine. Such an arrangement as herein described affords a simple 55 means of economically obtaining a maximum amount of power from a relatively small engine, owing to the greatly augmented volume of the charge, and provides an engine which is very flexible as the proportions of the mixture as well as the pressure and amount introduced into the cylinder or cylinders may be varied within wide 60 limits.

The operation of the device will be understood from the foregoing description. When

the engine is starting the mixing tube will, of course, function somewhat like the ordinary carburetor as the nozzle sprays the hydrocarbon into the tube. The engine then runs in much the same way that an engine 70 ordinarily operates and when heated the fuel flowing through the spiral 43 becomes vaporized before its projection into the mixing tube.

In case difficulty is experienced in starting the engine by means of fuel supplied by the nozzle 38 when the engine is cold, fuel mixture for starting may be supplied by means of the usual carburetor. This carburetor, however, is merely an auxiliary to 80 the mixing tube as the latter will supply a suitable mixture when the engine becomes hot enough to vaporize the fuel. The hydrocarbon pressure from tank 34 is supplied to the heating and vaporizing coil 43 by means of a pipe 37 and the gasoline discharging from the nozzle 38 expands and with the incoming air creates a high pressure in the mixing tube 22.

It will appear that the arrangement herein shown is capable of various modifications within the scope of the invention and I therefore do not intend to be limited to the exact details as shown and described.

I claim—

1. In a hydrocarbon engine, the combination with the cylinder having a mixture inlet, of a mixing tube communicating at one end with said inlet and having an air inlet and a hydrocarbon inlet at its opposite end, a pipe for supplying hydrocarbon to the latter inlet, a spiral in the line of said pipe supported upon and in contact with the outside of the head of the cylinder, and means for controlling the admission of air and hydrocarbon to said mixing tube.

2. In a hydrocarbon engine, the combination of a cylinder having a valve controlled fuel inlet, a U-shaped mixing tube having one end communicating with the fuel inlet, the other end of said U-shaped tube having an air inlet and a hydrocarbon inlet, a hydrocarbon supply tank, a spiral pipe connected to said hydrocarbon inlet and the hydrocarbon supply tank and supported on the cylinder in contact with the walls of the head of said cylinder, means for maintaining the hydrocarbon in the supply tank at a predetermined pressure, means for varying the amount of hydrocarbon supplied to the spiral pipe, and means for varying the effective area of the air inlet.

3. In a hydrocarbon engine, the combination of a cylinder having a fuel inlet, a U-shaped mixing tube having one end thereof communicating with the inlet, the other end of said tube flaring outwardly and being supported on the cylinder, there being a contracted section intermediate the ends of the tube, a conical member mounted on the

flaring end of the tube and having a plurality of air inlets therein, a shutter slidable on said member to vary the effective area of said air inlets, a nozzle mounted in said 5 conical member and shutter and adapted to discharge into the tube, a tank adapted to contain a liquid hydrocarbon, means adapted to maintain said hydrocarbon in the tank at a predetermined pressure, a pipe for delivering 10 hydrocarbon to the nozzle, a spiral in said pipe resting in contact with the head of said cylinder, a valve for varying the amount of hydrocarbon delivered to the nozzle, a steering column and means for operating the valve and shutter from the steering 15 column.

In testimony whereof I affix my signature in presence of two witnesses.

ABNER DOBLE.
